Primary Examiner — Selina Sikder(74) *Attorney, Agent, or Firm* — Altis Law Group, Inc.(57) **CLAIM**

The ornamental design for a cooling fin, as shown and described.

DESCRIPTION

FIG. 1 is a perspective view of a cooling fin showing my new design.

FIG. 2 is a front elevational view thereof.

FIG. 3 is a rear elevational view thereof.

FIG. 4 is a left-side elevational view thereof.

FIG. 5 is a right-side elevational view thereof.

FIG. 6 is a top plan view thereof; and,

FIG. 7 is a bottom plan view thereof.

The broken line showing of the cooling fan is for illustrative purposes only and forms no part of the claimed design.
